(57) **CLAIM**

The ornamental design for a bottle for cosmetics, as shown and described.

DESCRIPTION

FIG. 1 is a perspective view of a bottle for cosmetics of my new design;

FIG. 2 is a front view thereof, a rear view being identical to the front view;

FIG. 3 is a top view thereof;

FIG. 4 is a bottom side view thereof;

FIG. 5 is a right side view thereof, a left side view being identical to the right side view;

FIG. 6 is a sectional view thereof taken along line 6-6 in FIG. 2;

FIG. 7 is a perspective view thereof when a bottle cap is removed;

FIG. 8 is a front view thereof when a bottle cap is removed;

FIG. 9 is a top view thereof when a bottle cap is removed; and,

FIG. 10 is a right side view thereof when a bottle cap is removed.

In the drawings, the broken lines show portions of a bottle for cosmetics that form no part of the claim.
